UNITED STATES PATENT OFFICE.

WILLIAM JUDKINS, OF PESHTIGO, WISCONSIN.

DESIGN FOR A WINDOW-ROLLER BRACKET.

SPECIFICATION forming part of Design No. 26,074, dated September 22, 1896.

Application filed March 9, 1896. Serial No. 582,483. Term of patent 7 years.

To all whom it may concern:

Be it known that I, WILLIAM JUDKINS, a citizen of the United States, residing at Peshtigo, in the county of Marinette and State of Wisconsin, have invented and produced a new and original Design for Window-Roller Brackets; and I do declare the following to be a full, clear, and exact description of the same, reference being had to the accompanying drawings, forming a part thereof, in which—

Figure 1 is an edge view, and Fig. 2 a side elevation, showing the shape or configuration of my said bracket.

15 My design relates to the new and original shape of a window-roller bracket.

The leading features of this design comprise a central part flat on its under and partly rounded on its upper surface, this 20 part being shaped like the frustum of a cone, only drawn on a rounded line from the flat portion of the upper part to the base-line thereof, and with a downward-projecting portion extending from the center of the base or

under side of said central part, said projecting portion being of tapered and pointed shape, with a line of spiral corrugations its entire length, together with an upright flat straight-walled portion rising from the horizontal flat upper surface of the said central 25 part.

A minor feature of this design comprises a rounded extension of the just-described upright flat portion, which is flat and flush therewith on one side and on the opposite side is 30 increased in thickness, forming a rounded boss with flat outer surface similar in shape to the described central part of my design, but disposed at a right angle thereto.

What I claim is—

40 The design for a window-roller bracket, substantially as shown and described.

In testimony whereof I affix my signature in presence of two witnesses.

WILLIAM JUDKINS.

Witnesses:

W. G. BISHOP,
R. C. RAMSAY.
